UNITED STATES PATENT OFFICE

ROBERT H. LAWSON, OF PAWTUCKET, RHODE ISLAND, ASSIGNOR TO HEMPHILL COMPANY, OF CENTRAL FALLS, RHODE ISLAND, A CORPORATION OF MASSACHUSETTS

MEANS AND INSTRUMENTALITY FOR EFFECTING REVERSE PLATING

Original application filed May 10, 1926, Serial No. 107,921. Divided and this application filed May 28, 1929. Serial No. 366,540.

This application relates to improved means for effecting reverse plating in machines having independently operated needles, and this application is a division of my co-pending application Serial No. 107,921, filed May 10, 1926, now Patent No. 1,716,450, dated June 11, 1929.

In order that the principle of the invention may be readily understood, I have disclosed 15 a single embodiment thereof in the accompanying drawings, wherein—

Fig. 1 is a plan view representing the arrangement of the cams, sinkers, etc. in a circular, independent needle, knitting machine; 15 Fig. 2 is a vertical central section of the structure shown in Fig. 1;

Fig. 3 represents in perspective view the special instrumentality, a regular web holder and an instrument to even the dividing line 20 of plating between normal and reverse plating;

Fig. 4 represents in perspective a sequential arrangement of special instrumentalities and regular web holders for making narrow 25 stripes, particularly in fine gauge work;

Fig. 5 represents in six successive positions a needle, a special instrumentality and a regular web holder functioning in effecting 30 reverse plating, particularly for fine gauge work;

Figs. 5^a, 5^b, 5^c represent successive positions of the face and back yarns with relation to the needle in reverse plating; and

Fig. 6 is a detail in side elevation showing 35 in part means for feeding the yarns or threads in plating relation.

The machine herein disclosed as one upon which my invention may be practised need 40 not be specifically described inasmuch as it is shown, particularly in the parent application, as the well known Banner or Hemphill machine. Briefly it is to be noted that the machine is of the independent needle type and that the needles are desirably latch 45 needles. Therefore, I employ certain parts of that machine including a latch ring and narrowing and widening instrumentalities which need not be particularly referred to and which are not here shown. The needle cylinder is indicated at 18 and within the

grooves thereof are received the independently operated latch needles 19. At the upper end of the needle cylinder is provided the web holder receiving and operating mechanism which is generally similar to that of the Banner machine but altered in accordance with my invention. As here shown I have represented the web holder bed ring at 20. Positioned thereabove is the outer ring member 55 21 of the cam ring. The web holder bed ring 20 is provided with radial grooves indicated at 22 for the reception of the regular web holders, the special instrumentalities and the line eveners, as hereinafter referred to in detail. The special instrumentalities are indicated at A, the regular sinkers or web holders at B, and the line eveners at C. Said regular web holders B are desirably of typical or usual formation. They may be varied in accordance with operating conditions, and my invention is in no wise limited to the particular form thereof shown. Each such web holder (within which definition I include the so-called sinker) is mounted for in and out movement or radial sliding movement in a 60 groove such as 22 of the web holder bed ring 20, and in each groove thereof alongside of but desirably without mechanical connection therewith is provided the special instrumentality 65 or special sinker A.

The sinker cam ring which is provided with an annular formation 27 is at the proper point provided with a cam portion 31' for moving the web holders and special instrumentalities outward or for controlling or 70 limiting their inward movement. At opposite sides of the cam 31' are the stationary cams 32', 33' for moving the web holders and special instrumentalities inward.

Radially outside of the cam portion 31' and 75 at such a point as to engage with the outer end portions of the special instrumentalities A are two levers 34^a, 35^a, pivoted at 62 upon the knitting head, the shorter ends 63, 64 whereof are engaged by springs 65, 66, acting 80 normally to move the larger end of said levers into outer or non-functioning position. Said larger ends are shown as having cam formations or faces 67, 68, the function whereof is to 85 move the special instrumentalities A inward 90 and thereby move the web holders and special instrumentalities outward. The function of the 95

so as to cause them to push the back thread of normal plating into position to be the face thread of reverse plating (that is to say, so to act upon the thread or threads as to effect a reversal in the position of the threads). I provide means, preferably acting automatically, to move the longer ends of said levers 34^a, 35^a inward and have indicated a portion of the operating means as pins 43, 44, which need not be more particularly referred to, as the same constitutes no part of the present invention. The black yarn 90 is in normal plating the back yarn and the white yarn 91 is in normal plating the face yarn.

15 These two yarns are fed in plating relation, being supplied through two yarn guides 69', 70' mounted in the usual manner with the group of yarn guides so as to enter the throat 72 in the latch ring in a well understood manner. In proper relation to said yarn guides and the needles are positioned the knitting cams. The control of the two yarns or threads whereby they are introduced in plating relation desirably is that disclosed in my 20 Patent Reissue No. 16,584, dated April 5, 1927, the original application whereof was filed August 6, 1925.

The form of special instrumentalities A is particularly adapted to fine gauge work. It 30 is shown with a vertical flat yarn engaging face 75. A peculiarity of this form of special instrumentality and one which is peculiarly adapted to fine gauge work is the fact that leading from the upwardly inclined edge 76 of the nib 77 is a downwardly inclined and backwardly extending notch or groove 78. The function of this notch or groove is to engage the yarns or threads as most clearly shown in the several positions in Fig. 5 and 35 positively to guide or move them under definite control of the upper and lower faces of the said notch or groove 78, and particularly under the control of the upper face thereof. The upwardly and outwardly inclined edge 40 76 constitutes a wedge that serves to force the yarn or yarns more tightly against the shank of the needle. In effecting this wedging action the yarns passing over said wedge edge are lifted thereby and the downwardly inclined notch 78 serves to restore said yarns to the proper level with respect to the needle pertaining thereto. It is not essential that the notch or groove 78 be always associated 45 with a vertical yarn engaging edge, such as 75, since the former is capable of separate use in effecting reverse plating.

In Fig. 3, I have represented a group of members, the first of which is a special instrumentality A having the described vertical 50 face 75 and the downwardly and backwardly inclined groove 78. Considering the direction in which the knitting machine turns in regular knitting the special instrumentality is so positioned in a groove with a regular 55 web holder as first to engage the yarn or is

first in position with respect to the direction of travel.

In the same groove therewith is a regular web holder B and in the next groove, assuming that the line of reverse plating is but a single wale in width, is located the line evener C, the characteristic whereof is the upwardly and rearwardly sloping edge 79 serving to bring the yarn which has been acted upon by the face 75 of the special instrumentality down such sloping edge 79 so as to bring the said yarn into its proper position for normal plating. The rear end of the special instrumentalities A may be shaped as shown at 80 to be engaged by the proper cam lever and the rear end of the line evener C may be shaped as shown at 81, or otherwise as desired, so as to engage the proper cam lever.

It will be observed that I have provided mechanism for effecting plating and reverse plating in a knitted fabric, including a series of independent needles, thread engaging instrumentalities for each needle respectively, including regular web holders and including special instrumentalities where reverse plating is to be formed, all of said instrumentalities being movable individually transverse to the needle series, and thread guiding means to feed a back thread and a face thread in plating relation to the needles, each of said special instrumentalities having an outwardly and downwardly sloping edge adapted to receive at least one of said threads during loop formation and for the purpose of effecting reverse plating.

In Fig. 5, I have represented six successive positions assumed by the special instrumentality A in effecting reverse plating, particularly in fine work. The back yarn 90 appears as such in normal plating and the white yarn 91 is the face yarn of normal plating. In effecting reverse plating the edge 75 of the special instrumentality A engages the back yarn or thread 90 and in the ensuing movements of the special instrumentality and of the needle 19 the two yarns or threads respectively assume the positions shown in said figure. In Figs. 5^a, 5^b, 5^c I have represented successive positions of the yarns or threads 90 and 91 in forming reverse plating.

In my parent application, now Patent No. 1,716,450, certain forms of sinkers are shown having horizontal notches. The special instrumentality A having the outwardly and downwardly inclined groove 78 (referred to also as the downwardly and backwardly inclined groove) is also shown in said Patent No. 1,716,450, but, as stated in the specification of that patent, the construction of such special instrumentality is not claimed therein. As set forth beginning line 20, page 5 of the specification of that patent, a peculiarity of this form of special instrumentality particularly adapting it to fine gauge work is the said downwardly and backwardly inclined

grooves 78. Such form of special instrumentality is, however, in no sense limited to fine gauge work. In fine gauge work, however, the said outwardly and downwardly inclined groove 78, and particularly the lower edge thereof, cooperates with the needle in effecting the desired tightness of stitch.

The two yarns 90, 91 are reversed in position as clearly illustrated in Fig. 30 of said Patent No. 1,716,450 and in Fig. 5 of the drawings of this application.

Figs. 5^a, 5^b and 5^c show the position of the old loop knitted from the two yarns 90, 91 in several positions of the needle. In Fig. 5^a, the needle is descending and is in about the same position with respect to the special instrumentality A as in the fourth view of Fig. 5. In Fig. 5^b the needle is shown as having reached its lowest point of downward movement (namely, the casting off point), so that the two yarns 90, 91 are being cast off into the fabric. Such casting off point is about that shown in the sixth view of Fig. 5. In Fig. 5^c, the needle is shown as starting up again, the old loop having been fully cast off into the fabric.

The action of the outwardly and downwardly inclined groove 78 in effecting reverse plating is substantially the same as that disclosed in the British patent to Scott & Williams, Inc., No. 277,680 (convention date—United States September 17, 1926; complete specification—Great Britain—accepted February 16, 1929).

In Figs. 3 and 4, I have represented at C a so-called line evener, which forms no part of the present invention, being claimed in my said patent application. I will, however, briefly refer to the same. Difficulty was previously experienced in securing an even or regular line of demarcation between regular plating and reverse plating, since during the knitting operation there has been a liability that the line of demarcation may here and there advance or recede by a wale from the correct line. This difficulty is overcome in a manner fully described in my said parent application, and the specific embodiment of means disclosed for that purpose is a line evener, such as C. While such an instrumentality or device may in other forms of my invention be otherwise positioned, in the present disclosure I associate it with a regular web holder such as B, and therefore place it in the same groove as and with a regular web holder, and at such position in the machine that it is located next after the last special instrumentality that is then to perform or effect reverse plating; in other words, it is in the next radial groove considering the direction of rotation of the needle cylinder.

Having thus described one illustrative embodiment of my invention, it is to be understood that although specific terms are em-

ployed, they are used in a generic and descriptive sense and not for purposes of limitation, the scope of the invention being set forth in the following claims.

Claims:

1. Mechanism for effecting plating and reverse plating in a knitted fabric, including an upright circular series of independent latch needles, the points of the bills of said needles all being out of line with and in advance of the shanks of said needles, whereby the hooks of all of the said needles are truly concentrically positioned; thread engaging instrumentalities for each needle respectively, including special instrumentalities where reverse plating is to be formed; all of said instrumentalities being movable individually in and out radially to the needle circle in a horizontal path; thread guiding means to feed a back thread and a face thread in plating relation to the needles; each of said special instrumentalities having an outwardly and downwardly sloping edge adapted to receive at least one of said threads during loop formation and for the purpose of effecting reverse plating and means to impart an inward movement to desired thread engaging instrumentalities at an abnormally early point in the loop forming operation, whereby when a special instrumentality of the series is given said abnormally early inward movement, it receives at least one of said threads upon said outwardly and downwardly sloping edge during loop forming operation and reverse plating is effected at the corresponding needle, and whereby if said special instrumentality is not given said abnormally early inward movement, neither thread is received upon said outwardly and downwardly sloping edge and reverse plating is not effected at the corresponding needle.

2. Mechanism for effecting plating and reverse plating in a knitted fabric, including an upright circular series of independent latch needles; thread engaging instrumentalities for each needle respectively, including special instrumentalities where reverse plating is to be formed; all of said instrumentalities being movable individually in and out radially to the needle circle in a horizontal path; thread guiding means to feed a back thread and a face thread in plating relation to the needles; means to impart an inward movement to desired thread engaging instrumentalities at an abnormally early point in the loop forming operation; each of said special instrumentalities having an outwardly and downwardly sloping edge adapted to receive at least one of said threads during loop forming operation and for the purpose of effecting reverse plating at the corresponding needle, whereby when a special instrumentality of the series is given said abnormally early inward movement it receives at least one of said threads upon said

- outwardly and downwardly sloping edge during loop forming operation and reverse plating is effected at the corresponding needle, and whereby if said special instrumentality is not given said abnormally early inward movement neither thread is received upon said outwardly and downwardly sloping edge and reverse plating is not effected at the corresponding needle.
5. Mechanism for effecting plating and reverse plating in a knitted fabric, including a series of independent latch needles; thread engaging instrumentalities for each needle respectively, including special instrumentalities where reverse plating is to be formed; all of said instrumentalities being movable individually in and out transversely of the needle series; thread guiding means to feed a back thread and a face thread in plating relation to the needles; means to impart an inward movement transverse to the needle series to desired thread engaging instrumentalities at an abnormally early point in the loop forming operation; each of said special instrumentalities having an outwardly and downwardly sloping edge adapted to receive at least one of said threads during loop forming operation and for the purpose of effecting reverse plating at the corresponding needle; whereby when a special instrumentality of the series is given said abnormally early inward movement it receives at least one of said threads upon said outwardly and downwardly sloping edge during loop forming operation and reverse plating is effected at the corresponding needle, and whereby if said special instrumentality is not given said abnormally early inward movement neither thread is received upon said outwardly and downwardly sloping edge and reverse plating is not effected at the corresponding needle.
4. Mechanism for effecting plating and reverse plating in a knitted fabric, including a series of independent latch needles; thread engaging instrumentalities for each needle respectively, including special instrumentalities where reverse plating is to be formed; all of said instrumentalities being movable individually in and out transversely of the needle series; thread guiding means to feed a back thread and a face thread in plating relation to the needles; means to impart an inward movement transverse to the needle series to desired thread engaging instrumentalities at an abnormally early point in the loop forming operation; each of said special instrumentalities having an upper nib and below the top of said nib having a notch the lower edge of which is shaped to present an outwardly and downwardly sloping edge adapted to receive at least one of said threads during loop formation and for the purpose of effecting reverse plating at the corresponding needle; whereby when a special instrumentality of the series is given said abnormally early inward movement it receives at least one of said threads upon said outwardly and downwardly sloping edge and reverse plating is effected at the corresponding needle.
5. Mechanism for effecting plating and reverse plating in a knitted fabric, including a series of independent latch needles; thread engaging instrumentalities for each needle respectively, including special instrumentalities where reverse plating is to be formed; all of said instrumentalities being movable individually in and out transversely of the needle series; thread guiding means to feed a back thread and a face thread in plating relation to the needles; means to impart an inward movement transverse to the needle series to desired thread engaging instrumentalities at an abnormally early point in the loop forming operation; each of said special instrumentalities having a top nib provided with a substantially upright inner edge, and each said instrumentality having below said substantially upright edge a notch the lower edge of which is shaped to present an outwardly and downwardly sloping edge adapted to receive both of the said threads during loop forming operation and for the purpose of effecting reverse plating at the corresponding needle; whereby when a special instrumentality of the series is given said abnormally early inward movement it receives at least one of said threads upon said outwardly and downwardly sloping edge during loop forming operation and reverse plating is effected at the corresponding needle, and whereby if said special instrumentality is not given said abnormally early inward movement neither thread is received upon said outwardly and downwardly sloping edge and reverse plating is not effected at the corresponding needle.
- In testimony whereof, I have signed my name to this specification.
- ROBERT H. LAWSON.
